UNITED STATES PATENT OFFICE.

ADELARD J. PERRON, OF LEWISTON, MAINE.

CHAIR ATTACHMENT.

Application filed September 24, 1926. Serial No. 137,549.

In churches, convents, colleges and other places, folding chairs of ordinary well known construction are used during religious services, and there are no provisions made for those attending such services, to kneel upon, making it necessary to kneel upon the floor which is very uncomfortable to say the least.

The gist of the present invention resides in the provision of an attachment for chairs of this character, in the nature of a kneeling support, which can be quickly attached to or removed from any particular chair, and designed to permit the occupant of the chair to occupy a kneeling position with comfort.

In carrying out the invention the kneeling support is susceptible of adjustment toward and away from the back of the chair, so that it can be properly positioned with relation to the latter, for the specific purpose for which it is intended.

Another object of the invention resides in mounting the attachment on the chair in a manner to permit the attachment to be folded upwardly and between the legs of the chair in an out of the way position when its use is not desired, and in which position the chair can be folded in the ordinary manner without any interference on the part of the attachment.

The nature and advantages of the invention will be better understood when the following detail description is read in connection with the accompanying drawing, the invention residing in the construction, combination and arrangement of parts as claimed.

In the drawing forming part of this application like numerals of reference indicate similar parts in the several views and wherein:

Figure 1 is a side elevation of a chair showing the attachment associated therewith and arranged in position for use.

Figure 2 is a view taken at a right angle to Figure 1 and showing the attachment folded between the legs of the chair.

Figure 3 is a perspective view of the attachment.

Referring to the drawing in detail A indicates generally a folding or collapsible chair of ordinary well known construction, the legs of which are indicated at 10, and one pair of these legs are connected by a rung 11.

The attachment forming the subject matter of the present invention is in the nature of a kneeling support comprising a top mem-

ber 12 and end members 13 which are adapted to repose upon the floor when the support is in use in the manner clearly illustrated in Figure 1. The end members 13 are capable of being folded against the bottom of the top member 12 by ordinary hinges 13', when the support is not in use, so that the support may occupy a minimum of space, in an out of the way position between the legs of the chair as clearly shown in Figure 2. The end members 13 are held in extended positions for use by means of links 14, pivotally connected with each other and also with the top member 12 and end member 13, and arranged in the position shown in Figure 3 to hold the end members fixed relatively to the top member 12 for use. Projecting from one longitudinal edge of the top member 12 are supporting arms, each of which include sections 15 and 16 respectively. The section 15 is longitudinally slotted to receive the headed elements 17 carried by the section 16, which permits the latter mentioned section to be adjusted to vary the length of the arm, and also the distance between the chair and the kneeling support when the latter is arranged for use as shown in Figure 1. Each section 16 of the supporting arms terminates to provide resilient hook-like clamps 18 which are

adapted to embrace the rung 11 above mentioned, in a manner to permit the support to be mounted thereon for pivotal movement, so that the support in its entirety can be folded between the legs of the chair when desired as shown in Figure 2. At the same time these resilient clamps 18 allow the support in its entirety to be quickly attached to or removed from any particular chair with a minimum of time and effort.

In practice the attachment is clamped onto the rung of a chair as shown in Figure 1, and the support arranged in proper spaced relation to the back of the chair by adjusting or varying the length of the supporting arms above mentioned. When desired the attachment in its entirety can be folded between the legs of the chair as above mentioned, by simply folding the end members 13 against the adjacent side of the top member 12, and subsequently swinging the attachment upon the rung 11 to a position between the legs of the chair as shown in Figure 2. The chair can then be folded in the usual manner, and the chairs sacked one upon the other as is customary, without the attachment interfering with this procedure.

or the folding of the chair itself. The attachment can also be used in connection with chairs not having a rung connecting the back legs of the chair, in that any suitable means can be employed for pivotally connecting the kneeling support with the legs of the chair, and such is contemplated by the claim.

While it is believed that from the foregoing description, the nature and advantages of the invention will be readily apparent, I desire to have it understood, that I do not limit myself to what is herein shown and described and that such changes may be resorted to when desired as fall within the scope of what is claimed.

What is claimed is:

A chair attachment, comprising a kneeling support having a top member, and end members depending therefrom and capable of being folded against one side of the top member, pivoted links for holding said end members extended for use, arms projecting from the top member and designed to be detachably associated with a rung of the chair, and permit said support to be moved pivotally to a folded position between the legs of the chair when not in use, and said arms including relatively adjustable sections to vary the length of the arms for the purpose specified.

In testimony whereof I affix my signature.

ADELARD J. PERRON.
